H. G. GILLMOR,
RAIL ANCHOR,
APPLICATION FILED MAY 19, 1916.

1,278,633.

Patented Sept. 10, 1918.

UNITED STATES PATENT OFFICE.

HORATIO G. GILLMOR, OF WASHINGTON, DISTRICT OF COLUMBIA.

RAIL-ANCHOR.

1,278,633.

Specification of Letters Patent. Patented Sept. 10, 1918.

Application filed May 19, 1916. Serial No. 98,529.

To all whom it may concern:

Be it known that I, HORATIO G. GILLMOR, a citizen of the United States, residing at Washington, in the District of Columbia, 5 have invented certain new and useful Improvements in Rail-Anchors, of which the following is a specification.

My invention relates to a rail anchor, anticreeper or rail stay and the principal 10 object of the invention is to provide a device which may be used in connection with and attached to a tie plate, which will be simple in construction, light in weight, inexpensive to manufacture and which will 15 effectually hold the rail, will not be loosened by vibration, changes of temperature or other causes that tend to impair the grip or holding power which is essential to the efficiency of a device of this character.

20 A further and specific object of the invention is to provide a novel form of rail anchor utilizing spring pressure for effecting and maintaining a grip of the device upon the rail.

25 A further object is to provide a device which is wedged against both the head and the base flange of the rail in such manner that the holding power of the device under all conditions will be good.

30 A further object of the invention is to provide a device the grip of which on the rail will not be affected by retrograde movement of the rail that is, movement of the rail in a direction the reverse of the normal 35 creep.

The invention is illustrated in a preferred embodiment, in the accompanying drawing, wherein—

Figure 1 illustrates, in elevation, the 40 structure constructed in accordance with the invention, applied to a rail which is shown in section. Fig. 2 is a side elevation of the device and the tie plate showing a portion of the rail and the tie. Fig. 3 is a section 45 of the parts at the plane indicated by the line X X in Fig. 2, showing the device in one of the positions assumed while the device is being applied. Fig. 4 is a plan view of the parts shown in Figs. 1 and 2.

50 Like characters of reference designate like parts in the several figures of the drawing.

In the drawing A represents a railway 55 rail of the usual construction having a head B and a base flange C, resting upon a tie plate D which may be any one of the several

kinds of tie plates ordinarily used in railway construction, having spiking apertures such as E some of which are traversed by spikes F which are driven into the tie G 60 upon which the tie plate D rests supporting the rail thereon. Engaging a spiking aperture E at one side of the rail, is the rail engaging and gripping part H the portion I of which engages the spiking aperture E 65 in the tie plate D. The part H is constructed with a recess K arranged to receive a spring L, here shown helical in form and guided by the portion M of the part H. The part H is provided with a surface 70 N which engages the under surface of the head B of the rail and a stiffening rib O with an enlarged portion P is provided for strengthening the part H. To provide properly for the spring aperture or recess 75 K the part H is constructed with a bossed portion R within which the recess K is formed.

The device is placed in position by inserting the portion I of the part H in the 80 spiking aperture E of the tie plate D with the spring L in place in the recess K and moving the part H with the portion I engaging the aperture E to the position shown in Fig. 3 when the surface N will begin to 85 engage the under surface of the head B of the rail A. In this position the spring L is exerting a pressure upon the part H in a direction normal to the upper surface of the base flange C of the rail and one component 90 of the pressure exerted by the spring is tending to push the part H upward and the other component of the spring pressure is tending to push the part H out from the rail. The upward pressure is resisted by 95 the engagement of the surface N of the part H with the under surface of the rail head B and the pressure tending to push the part H out from the rail is resisted by the engagement of the portion I of the part H with the 100 spiking aperture E in the tie plate D. The tie plate D may be formed with a projecting portion Q to engage the edge of the rail base C at the side of the rail opposite to the part H or the spikes F may be employed to hold 105 the tie plate in position and resist the lateral pressure exerted upon the tie plate D by the portion I of the part H. From the position of the part H shown in Fig. 3 it may be driven or forced with a suitable 110 wrench to the final operative position illustrated in Figs. 1, 2 and 4. The spring will,

by this forcing of the part H into place, be compressed and in the final operative position of the device the rail base C and the under side of the rail head B will be 5 strongly gripped by the part H and the spring L and the spring L in its compressed or flattened condition will exert a strong pressure upon the upper surface of the rail base flange C and upon the part H. The 10 engagement of the portion I of the part H with the aperture E in the tie plate D will hold the part H against lateral displacement and the part H and the spring L gripping the rail A firmly hold the rail against 15 longitudinal or creeping movement by the engagement of the portion I of the part H with the tie plate D.

As will be apparent from the above description and drawing the anchor is adapted 20 to prevent the rail from moving longitudinally in either direction so that tendency of the rail to move in a direction the reverse of that in which the general tendency of the rail is to creep will not affect the grip of 25 the device upon the rail. Moreover the anchor is reversible and may be applied to either side of the rail as may be dictated by local conditions.

Although the device is herein shown and 30 described in its preferred embodiment, it will be understood that changes and modifications may be made without departing from the spirit of the invention and all such changes and modifications are contemplated 35 as fall within the scope of the claims.

What I claim and desire to secure by Letters Patent is:

1. A device for preventing the creeping 40 of rails including a member adapted to engage the under side of the head of a rail and a tie plate at one side of the rail and yielding means engaging said member and the upper surface of the rail base for holding said member in engagement with the 45 rail head and the tie plate.

2. A rail anchor including a part adapted to engage a tie plate and to be forced in between the under side of the head and the upper side of the base flange at one side of 50 a rail and a spring engaging said part and the upper side of the rail base flange and exerting pressure thereon to cause said part to grip the rail.

3. An anticreeping device including a rail 55 engaging member adapted to engage a tie plate and the under surface of the rail head at one side of the rail and a spring held in a recess in said member and bearing against the rail for holding said rail engaging member in position.

4. A device for preventing the creeping 60 of rails including an element adapted to engage the rail head and a tie plate at one side of the rail and yielding means forcing 65 said element up against the rail head.

5. A rail stay including a piece adapted to fit in between the head and base flange of a rail and to engage a spiking aperture in a tie plate at one side of the rail and a spring bearing against the rail base and said piece to hold said piece pressed up against the rail head. 70

6. A device for preventing the creeping of rails including a part arranged to be applied to the rail between the head and the base flange and engage a tie plate at one side of the rail and a spiral spring engaging the rail base and said part to hold said part in gripping engagement with the rail. 75

7. A rail anchor comprising a member 80 designed to be held between the rail head and base flange and provided with an arm projecting below the rail base at one side of the rail, a holding plate formed with an opening receiving said arm and yielding 85 means for pressing said member up against the rail head.

8. An anticreeping device comprising a part adapted to be applied to the rail between the head and the base thereof and 90 provided with a projection extending below the rail, means for forcing said part up against the rail head and a holding plate formed with an aperture receiving said projection, the engagement of said projection 95 and the walls of said aperture preventing both transverse and longitudinal movement of said piece.

9. A device for preventing the creeping 100 of rails comprising a member adapted to be applied to one side of the rail between the head and the base flange, a spring bearing upon the base flange and pressing said member up against the rail head and a tie plate so engaging said member as to hold the 105 same in position.

10. A rail anchor comprising a part engaging the underside of the head of the rail and projecting beyond the edge of the base flange at one side of the rail, a spiral spring bearing upon the upper surface of the base flange of the rail and a tie plate so engaging said part as to hold said part in position. 110

11. A tie plate attachment for preventing the creeping of rails comprising a rail engaging member adapted to engage a tie plate and the under surface of the rail head at one side of the rail and a resilient part engaging said member and the upper surface of the rail base. 115

12. An anticreeping attachment for tie plates comprising a member engaging the under surface of the rail head, the edge of the rail base flange and a tie plate at one side of the rail and a spring intervening between said member and the upper surface of the rail base flange. 120

13. A rail anchor comprising a transverse part engaging one edge of the rail base, a vertical member constructed to engage said 130

- transverse part, the rail base edge and the under side of the rail head at the other side of the rail and a spring engaging said member and the upper surface of the rail base.
- 5 14. An anticreeper for rails comprising a rail base engaging element provided with means for engaging the edge of the rail base at one side of the rail, a spring engaging the upper surface of the rail base at the other side of the rail, and a vertically disposed part, so engaging said element the spring and the rail head at the other side of the rail, that, when forced in between the head and the base flange of the rail, a transverse pull is exerted by said part upon said element and vertical pressure is exerted by said part upon the spring and the rail base, and means for giving said element a fixed position in the roadbed.
- 10 15. A rail anchor comprising a spring adapted to engage the upper surface of the rail base flange at one side of the rail and a part adapted to fit in between the spring and the rail base head and to engage a spiking aperture in a tie plate at one side of the rail.
- 15 16. A device for preventing the creeping of rails comprising a part arranged to be applied to the rail between the head and the base flange of the rail and to engage a tie plate at one side of the rail and to be locked into position by the engagement of said part with the under surface of the rail head and a spring which intervenes between said part and the rail.
- 20 17. An anticreeper comprising a transverse member, having means for engaging the edge of the rail base at one side of the rail, a spring engaging the upper surface of the rail base at the other side of the rail, a part which engages said spring the under side of the rail head and said transverse member and means for giving said anticreeper a fixed position in the roadbed in opposition to the tendency of the rail to creep.
- 25 18. A rail anchor comprising a transverse member, held to the tie, having an abutment at one side of the rail, a spring engaging the rail base at the other side of the rail and a vertical element which engages said spring, said member and the under side of the rail head.
- 30 19. A device for preventing the creeping of rails comprising a tie plate having means for engaging the rail base at one side of the rail, a spring which engages the rail base at the other side of the rail and a part which engages said transverse member, the spring and the under side of the rail head.
- 35 20. A rail anchor comprising a tie plate provided with means for engaging the rail base edge at one side of the rail, a spring engaging the rail base at the other side of the rail and a part, engaging the tie plate, the
- spring, and the rail head, locked in position by pressure exerted by said spring.
21. A device for preventing the creeping of rails comprising a part adapted to be applied to the rail between the head and base flange thereof and provided with a portion extending below the rail, a spring engaging the rail base and said part and a holding plate formed with an aperture receiving and so engaging said portion as to subject said part to stress and to prevent both transverse and longitudinal movement of the lower end of said part
- 70 22. An anticreeper comprising a member arranged to be applied to the rail between the head and the base flange thereof and to extend below the rail base flange at one side of the rail, a tie plate engaging said member and a spring intervening between the rail base and said member.
- 75 23. A device for preventing the creeping of rails comprising a transverse member provided with means for engaging the rail base edge at one side of the rail, a spring engaging the rail base at the other side of the rail, a part engaging said member and arranged to be driven in between said spring and the head of the rail and means for giving the device a fixed position in the roadbed.
- 80 24. A device for preventing the creeping of rails comprising a tie plate provided with means for engaging one edge of the rail base, a spring engaging the rail base and a part engaging the tie plate and arranged to be driven in between said spring and the rail head.
- 85 25. An anticreeper comprising a transversely extending element provided with means for engaging the edge of the base flange of the rail at one side, a spring engaging the rail base at the other side of the rail and a vertically disposed part constructed to engage said element and said spring and to be driven in between the head and the base of the rail to affect the gripping action.
- 90 26. In a rail anchor, the combination of a transverse element adapted to engage one edge of the rail base, a vertical element adapted to engage said transverse element and the rail head at the other side of the rail, a yielding member intervening between the rail base and said vertical element and means for giving said anchor a fixed position in the roadbed.
- 95 27. In an anticreeper, the combination of a transverse element adapted to engage a rail base at one side of the rail, a vertical member engaging said element and the rail head at the other side of the rail, a spring which intervenes between the rail base and said vertical member and means for giving said anticreeper a fixed position in the roadbed.
- 100 28. In a rail anchor, the combination of a

- transverse element provided with means for giving said element a fixed position in the roadbed and gripping means which intervene between the rail head and base flange 5 comprising a vertical part engaging said element and a resilient member which bears against the rail and said member.
29. In a rail anchor, the combination of a transverse element provided with means for 10 giving said element a fixed position in the roadbed and gripping means applied between the rail head and the rail base flange comprising a resilient member bearing

against the rail and a rigid member which has a projection at one end engaging said 15 transverse element.

30. In a rail anchor, the combination of a transverse element adapted to engage the rail base at one side of the rail, a rail head engaging part, engaging said element at the 20 other side of the rail, a spring which intervenes between said part and the rail base and means for giving said anchor a fixed position in the roadbed.

H. G. GILLMOR.
